DESIGN FOR A CHILD'S PLAY TABLE

Emmons A. Goddard, Detroit, Mich.

Application February 26, 1937, Serial No. 67,878

Term of patent 14 years

To all whom it may concern:

Be it known that I, Emmons A. Goddard, a citizen of the United States of America, residing at Detroit, in the county of Wayne and State of Michigan, have invented a new, original, and ornamental Design for a Child's Play Table, of which the following is a specification, reference being had to the accompanying drawing, forming a part thereof.

In the drawing:

Fig. 1 is a perspective view of the play table showing the seats in extended relation for use.

Fig. 2 is a side elevation showing the seats in the folded position when not in use.

I claim:

The ornamental design for a child's play table as shown.

EMMONS A. GODDARD.
